UNITED STATES PATENT OFFICE

2,654,627

OIL FIELD FISHING TOOL FOR ROCK BITS

Drew Story, Hobbs, N. Mex.

Application July 11, 1949, Serial No. 104,080

4 Claims. (Cl. 294—65.5)

1

This invention relates to novel and useful improvements in fishing tools to be used in oil fields.

An object of this invention is to recover rock bits, or any other metallic or magnetizable tool or article which for one reason or another becomes lodged or submerged in a shaft in the ground thereby rendering further operations in the shaft substantially impossible until such time as the lost article has been recovered.

Another object of this invention is to utilize a magnet of one form or another which is disposed in a sectional case adapted to be lowered in the shaft or in the ground and which includes cutter teeth at the lower end thereof together with a liner of insulating material separating the magnet from the actual case.

Ancillary objects and features of novelty will become apparent to those skilled in the art, following the description of the preferred forms of the invention, illustrated in the accompanying drawings, wherein:

Figure 1 is a longitudinal sectional view of one form of the invention;

Figure 2 is a sectional view taken substantially on the line of 2—2 in Figure 1 and in the direction of the arrows;

Figure 3 is an elevational view, parts being shown in section, of a second form of the invention, differing from the first in that a different type of magnet is utilized;

Figure 4 is a sectional view taken substantially on the line 4—4 of Figure 3 and in the direction of the arrows;

Figure 5 is a fragmentary sectional view of a third form of the invention, differing from the other two forms in that another type of magnet is utilized that is, one which has a battery used in conjunction therewith; and

Figure 6 is a transverse sectional view taken on the line 6—6 in Figure 5 and in the direction of the arrows.

The illustrated forms of the invention have substantially identical casings. Each casing is composed of a dome section 10 connected with a second section 12 which is, in turn, connected with a bottom section 14. Any number of sections may be interposed in this system, it being only necessary to provide external threads at the ends of the casing so that the union 16 may be applied. Gaskets, if found desirable, may be interposed in the joints.

The dome section 10 has an eye 18 at the top thereof adapted for attachment with a cable which may be fixed to a winding drum for lowering purposes.

2

The lower section 14 is provided with a number of teeth 20 along the lower bottom end of the substantially cylindrical case. The teeth are used for leading the tool in the ground.

5 The dome section 10 of the base is provided with an opening (unnumbered) which may be plugged when the magnet of the illustration of Figure 1 or 2 is used but which is put to use in the embodiment of the invention shown in Figure 3. A small grommet 26 is disposed in the opening within the dome section 10 and has electrical conductors 28 passed therethrough. These conductors are fixed to the contacts 30 and 32 which are disposed in the electrically insulating plate 34 of the electro-magnet 36.

10 An electrically insulating liner 40 is disposed in the case and is used for the purpose of insulating the electro-magnet 36 from the case sections and also for the purpose of insulating the permanent magnet 42 from the case sections.

An electrically insulating liner 40 is disposed in the case and is used for the purpose of insulating the electro-magnet 36 from the case sections and also for the purpose of insulating the permanent magnet 42 from the case sections.

15 Referring specifically to Figure 1 there is a cross bar 44 composed of two parts which are passed through threaded openings in the case section 12 and which are connected together by the union 46. An eye bolt 48 depends from the bar or support 44 and has one end threaded in a boss 50 which is fixed to the permanent magnet 42. A sleeve type liner 54 is disposed on the outside surface of the permanent magnet for contact with the insulating liner 40.

20 Referring now specifically to the embodiment of the invention shown in Figure 3, substantially the same structure is utilized including the eye bolts 48 however, the described insulating plate 34 is used as the recipient of threaded end of the eye bolt 48. The substantially conventional electro-magnet 36 which is disposed in the case is spaced from the insulating liner 40 by means of the sleeve type member 58 which is disposed around the electro-magnet.

25 Reference is now made to Figure 5, wherein the final embodiment of the invention is illustrated. The differentiating feature is the utility of a battery 60 which is disposed in the case and which has the lead wires 62 and 64 extending therefrom and terminating in appropriate terminals of the electro-magnet 66. In order to fasten the electro-magnet 66 ultimately to a cross member identical to that seen at 44, the boss 68 on the top of the electro-magnet has a short length of threaded shank 70 disposed therein and also disposed in another boss 72 which is carried by the battery 60. This connects the electro-magnet with the battery from a mechanical standpoint. The boss 76 which is fixed to the

top of the battery 60 receives the eye bolt 78 therein.

In operation the device is lowered into the ground for the purpose of recovering lost articles of a magnetizable nature. By the above described structure this is capable. If the weight of the device is insufficient, it is only necessary to weight the device further by the addition of another section similar to that shown at 12. Upon contacting the metallic element, the device is brought up by means of a drum and cable or the like.

Having described the invention, what is claimed as new is:

1. A device for recovering rock bits comprising a substantially cylindrical sectional case having an open bottom end with a plurality of teeth therearound, a lining of insulating and cushioning material in said case and substantially covering the inner wall of said case, a transverse bar fixed within said case and having a magnetic element carried thereby for magnetically attracting lost articles, said lining being disposed between said magnetic element and said case.

2. In a device for recovering articles of magnetizable material, a case consisting of a plurality of sections releasably connected together, a lining of insulating material disposed in said case, a transverse support supported by and disposed in and extending across said case, a magnetic element disposed in said case, and means secured to said support maintaining said element in said case, said lining being disposed between said magnetic element and said case.

3. In a device for recovering articles of magnetizable material, a case consisting of a plurality of sections releasably connected together, a

lining of insulating material disposed in said case, a transverse support supported by and disposed in and extending entirely across said case, a magnetic element disposed in said case, and means secured to said support maintaining said element in said case including a vertically disposed bolt, a battery fixed to said bolt and electrically connected with said element.

4. In a device for recovering magnetizable articles from a well shaft, a casing having an open lower end, a lining of resilient and insulating material disposed in said casing and substantially covering the inner wall of said casing, an element disposed in said casing and spaced therefrom by said lining, said element being magnetic to attract the magnetizable articles, and means attached to said casing for supporting a lowering and lifting means, said lining being disposed between said magnetic element and said case.
